UNITED STATES PATENT OFFICE.

JOHN L. CREVELING, OF NEW YORK, N. Y.

ELECTRIC TRAIN OR VEHICLE.

No. 922,752.

Specification of Letters Patent.

Patented May 25, 1909.

Application filed March 26, 1903, Serial No. 149,685.

To all whom it may concern:

Be it known that I, JOHN L. CREVELING, a citizen of the United States, residing in the city, county, and State of New York, have 5 invented a certain new and useful Improvement in Electric Trains or Vehicles, of which the following is a specification, reference being had to the drawing forming a part thereof.

10 My invention pertains to that class of trains made up of detachable vehicles as of cars and adapted to run over an ordinary track as used in regular railroad practice now employing the steam locomotive to draw 15 trains made up of detachable cars and has for its particular object to produce means whereby fuel may be carried upon the train and energy derived therefrom be utilized to produce torque upon the wheels of several of 20 the vehicles composing the train by means distributing the energy derived in what might be called the locomotive to motors throughout the train tending to rotate several of the wheels of the various vehicles 25 upon which rest the weight of the train and therefore causing the tractive effort to be a function of the weight of the entire train rather than that of the locomotive merely as in ordinary steam railroad practice.

30 Figure I of the drawing illustrates diagrammatically one form of train embodying my invention. Fig. II. illustrates diagrammatically a locomotive similar to the one shown in Fig. I. in which internal combustion 35 motors are depicted in place of the steam turbines of Fig I.

Like numerals in the figures are used to indicate like parts.

Referring to the drawing, particularly Fig. 40 I., (1) represents the vehicle in which the energy used for propelling the train is derived from the fuel. (2) represents any suitable sort of tender for the transportation of the fuel. (3) represents a car of any 45 suitable type such as may be used in making up the train. (4) represents the boiler, in this instance merely indicated as of the marine type, readily permitting the use of the corrugated suspension furnace and adapted 50 to generate steam at the expense of fuel of any description as coal, oil, etc., which may be carried in the tender (2). From the boiler (4) the pipe (5) leads to what might be termed a steam controller (6) from which 55 is led the rod (7) to the lever (8) serving to

actuate said controller. The numerals (9) indicate prime movers adapted to produce rotary motion at the expense of the energy derived from the fuel, in this instance being indicated diagrammatically as steam turbines and readily controllable by the engineer through the instrumentality of the lever (8) and apparatus coöperating therewith. From these motors the exhaust may be led away in any suitable or desired manner. The 60 numeral (11) indicates dynamos or generators direct connected with the turbines (9) and from which the leads (12) are carried to a suitable electric controller (14) provided with operating handle (15) and reversing 65 lever (16). The field circuits of the generators may be carried as by cable (13) to controller (14) and governed by the engineer through the instrumentality of lever (20). (17) represents the cable leading from the 70 controller (14) and is connected from car to car as by flexible connection (18) and is connected with regard to the controller (14) and the various motors (19) in operative relation to the various wheels of the several cars 75 as to be capable of rotating the same, so that the said motors are under control of the controlling device designated as (14).

A practical operation of my improved system is as follows: Fuel is taken from the 80 tender (2) and used for the production of steam in the boiler (4) which passes through pipe (5) and steam controller (6) to the several prime movers or motors located in this car or locomotive and under control of the engineer as by lever (8). In starting the train 85 the motors or turbines may be started and brought to the proper speed by means of lever (8) and the generators may be regulated to give their required voltage as by means of lever (20) governing the fields thereof. Current may be taken from the generators and fed to the various motors throughout the train as by feeders (17) and (18) and controlled as in any of the ordinary multiple 90 unit systems by means of controller (14) operated by the engineer by means of lever (15). In this way the energy derived from the consumption of the fuel can be caused to 95 rotate the wheels throughout the train by 100 the various motions in such manner as to greatly increase the tractive effort above that of the locomotive whose draw-bar pull is a function of its own weight upon the rails. The train may be run and regulated in this 105 110

manner as may be desired and in stopping the current may be properly regulated by the lever (15) and the motors (9) allowed to revolve or stop as may be deemed proper according to the length of time of the said stop.

It will be noticed that I have shown the generators as mounted in pairs and it will be obvious that these may be connected in multiple or in series with each other and may be connected from the controller so as to operate in multiple to produce a large current of comparatively low voltage if desirable in order to create a great starting torque, and afterward connected in series to increase the speed of the train after the same has attained a reasonable speed. In this way the electric motors throughout the train can be overloaded for a short time without injury and the prime movers can be run at their maximum speed or output during said starting, thus greatly increasing the acceleration.

It will also be obvious that throughout all changes in load and speed the prime movers may be run at practically their maximum speed and efficiency and that at all times the control of all the driving motors arranged throughout the train will be directly under the engineer having also the control of the prime motors.

It will be obvious that any kind of fuel may be used and that an internal combustion motor, or any other motor deriving its energy direct without the intervention of boilers or other such means, may be employed, also that any number of motors and generators may be employed and have their mutual relations altered in any desired manner, and that only part of the motors may be used when drawing light trains and the whole equipment pressed into service when drawing heavy trains, or any other such combinations be made as desired, without departing from the spirit of my invention.

The above description of the construction and operation of my improvement in electric trains, with reference to Fig. I. may be readily understood with respect to Fig. II., in that, all of the electric devices, connections, and operations are the same in the locomotives shown in Fig. I. and II. and, indicated by the corresponding numerals, and the internal combustion motors (9) perform the same functions as the steam driven motors of Fig. I., while (6) represents the throttle of the motors (9), to which the charge may be led from any suitable source, as indicated by the pipes (5), said throttle (6) being under control of the engineer, as by lever (8).

I do not wish in any way to limit myself to any construction shown in the drawing which is merely a diagram illustrating one form of my invention and from which great variation may be made and still within the scope of said invention.

Having thus described my invention, what I desire to protect by Letters Patent is as set forth in the following claims, to wit:

1. A train comprising a unit or vehicle provided with a prime mover, or prime movers and means controlling the operation thereof and a plurality of dynamos operated by said prime mover or prime movers and means controlling said dynamos and means controlling the mutual relations of said dynamos, in combination with one or more vehicles provided with motors, the operation of which tends to move the train and means controlling the mutual relations of said motors in accordance with changes in the mutual relations of the dynamos. 75

2. A train comprehending a unit or vehicle provided with a prime mover or prime movers, means controlling the operation thereof, a plurality of dynamos operated by said prime movers or prime mover, means controlling said dynamos and means connecting said dynamos to work together in series and in multiple, in combination with one or more units or vehicles provided with motors the operation of which tends to move the train and means connecting said motors to work in series and in multiple with each other and with the said dynamos. 90

3. A unit or vehicle upon wheels, with a plurality of dynamos, a prime mover or prime movers operatively connected with said dynamos, a plurality of motors operatively connected with said wheels, means whereby said dynamos may be connected in multiple and in series with each other, and means whereby said motors may be coupled in series and in multiple with each other, in such manner that the dynamos may be coupled in multiple with each other to supply current to the motors in series with each other, and that the dynamos may be coupled in series with each other to supply current to the motors in multiple with each other. 100

4. A unit or vehicle upon wheels, with a plurality of dynamos, a prime mover or prime movers operatively connected with said dynamos, a plurality of motors operatively connected with said wheels, means whereby said dynamos may be connected in multiple and in series with each other, means whereby said motors may be coupled in series and in multiple with each other, in such manner that the dynamos may be coupled in multiple with each other to supply current to the motors in series with each other and that the dynamos may be coupled in series with each other to supply current to the motors in multiple with each other, and means for controlling the operation of said prime mover or prime movers. 110 115 120 125

5. A train comprising a unit or vehicle upon wheels, with a prime mover or prime movers, a plurality of dynamos in operative connection with said prime mover or prime 130

movers, and means for controlling said prime mover or prime movers, and a unit or vehicle upon wheels, with a plurality of motors in operative connection with said wheels, and 5 means whereby said dynamos may be connected in multiple and with said motors in series, for operation of the motors at low speeds and whereby said dynamos may be connected in series and with the motors in

multiple, for operation of the motors at high 10 speeds.

In testimony whereof I have signed my name to this specification in the presence of two subscribing witnesses.

JOHN L. CREVELING.
